UNITED STATES PATENT OFFICE.

MARCUS M. WILCOX, OF NEW BEDFORD, MASSACHUSETTS, ASSIGNOR OF
ONE-FOURTH TO JESSE GIFFORD, OF SAME PLACE.

NECK-BAND FOR BOTTLES.

SPECIFICATION forming part of Letters Patent No. 392,390, dated November 6, 1888.

Application filed February 15, 1888. Serial No. 264,153. (No model.)

To all whom it may concern:

Be it known that I, MARCUS M. WILCOX, a citizen of the United States, residing at New Bedford, in the county of Bristol and State of Massachusetts, have invented a new and useful Improvement in Neck-Bands for Bottles, of which the following is a specification.

My invention consists of a strip of metal adapted to be clamped around the neck of a bottle and having integral projections from its lower edge, under which the wire used to wire down the cork may be passed and thereby securely held; and the object of my invention is to facilitate and cheapen the operation of wiring bottles.

In the drawings, Figure 1 is a view of the metallic strip before being clasped around the neck of a bottle. Fig. 2 is an end view of the same. Fig. 3 is a view of the neck of a bottle with my invention applied.

In Fig. 1, *a* represents the metallic strip, cut, as shown in the drawings, to provide projections *b* in its lower edge, and having the tongue *d* and slot *c* as means whereby it is clasped around the neck of a bottle, as shown in Fig. 3.

In Fig. 2, *a* represents the metallic strip,

and *b* one of the projections in its lower edge, which is bent outward and downward, as shown, in order that the wire may be passed underneath it.

In Fig. 3, *e* represents the neck of a bottle having the metallic strip *a* clasped around it and the cork *h* held down by the wires *g* passing under the projections *b*. The metallic strip *a* is designed to always remain clasped around the neck of the bottle.

I am aware that it is not new to provide a metallic band adapted to clasp the neck of a bottle and provided with projections outstanding from its upper edge, under which a wire to hold the cork is passed, and such I do not claim.

Having thus described my invention, what I claim, and desire to secure by Letters Patent, is—

The herein-described metal band adapted to be clasped around the neck of a bottle, said band having integral projections from its lower edge, substantially as described and shown.

MARCUS M. WILCOX.
